UNITED STATES PATENT OFFICE

WALTER P. GISSKE, OF CHICAGO, ILLINOIS, ASSIGNOR TO VAUGHAN NOVELTY MFG. CO.,
OF CHICAGO, ILLINOIS, A CORPORATION OF ILLINOIS

CAN OPENER

Application filed February 24, 1931. Serial No. 517,871.

This invention relates to improvements in can openers and more particularly to can openers of the stationary type designed to be mounted on a wall or table, and operated by the turning of a crank to cut the top from the can.

The object of the invention is to provide an improved construction for openers of the so-called stationary type, and characterized generally by a pivoted cutting blade having a handle for forcing it through the top of the can after it has been placed in the opener and a crank-operated traction wheel or disc for rotating the can after the cutting blade has punctured the top.

A further object of the invention is to provide a novel arrangement of guide members in the form of lugs which bear upon the edge of the can on opposite sides of the point of cutting and thus insure positive and otherwise entirely mechanical cutting action.

A preferred embodiment of the invention is disclosed in the accompanying drawings, in which

25 Figure 1 is a perspective view of the opener from the rear as mounted on a wall or vertical surface.

Figure 2 is a perspective view of the same opener from the front, but shown as mounted 30 on a table or other horizontal surface.

Figure 3 is an enlarged detail view of the operating parts in elevation, and

Figure 4 is a view in vertical section taken on line 4—4 of Figure 3.

35 For a stationary mounting, the operating parts of the opener are located at the outer end of an arm 1 adjustably connected at its inner end to a bracket 2 adapted to be fastened as by screws to a wall, woodwork or table, with the arm 1 projecting horizontally therefrom at a distance to afford ample clearance for convenient operation. As shown in Figures 1 and 2, the arm is connected with the bracket 2 so that the latter can be secured

45 to either a vertical or horizontal surface and the arm will project horizontally in either case. The bracket 2 is an angle plate with one flange projecting at right angles from the surface to which the other flange is fastened as by screws 3. Projecting from the

outer face of the projecting flange are two short cylindric lugs 4 located on opposite sides of a bolt 5 extending through the center of the flange and in diagonally opposed corners thereof. The arm 1 which has the form of a strip of metal flanged along its edges as at 1a has at its inner end a group of four smaller holes 6 grouped symmetrical about the center bolt 5 and arranged in diagonally disposed pairs, either one or the other being adapted to register with the lugs 4 on the face of the bracket flange. The bolt 5 is equipped with a wing nut 5a which, on being loosened, permits the bracket 2 and arm 1 to be adjusted through an angle of 90° 55 for wall or table mounting.

At the outer end of the arm 1 is preferably mounted a plate 7 acting as a base for the operating parts of the opener, although the end portion of the arm itself may serve the purpose. As shown, however, the separate plate 7 is welded or otherwise fastened to the arm with its main portion projecting beyond the overlapping inner end portion.

The outer portion of the plate 7 moreover 75 is canted slightly into a plane oblique to the plane of the supporting arm 1, as the result of swaging the plate along a transverse line 7a just beyond the end of the arm. Thus as shown in Figure 4 the outer end of the plate 80 inclines slightly to the left at its upper end.

Near the bottom edge of the plate 7 and centrally of its projecting main portion is a disc 8 with a toothed periphery lying flatwise in close contact with one face of the 85 plate, and on the opposite side of the plate is a crank 9 having a long arm with a handle 9a at its end. The tooth wheel or disc 8 and the crank 9 are both fixed to the ends of a pin 10 journaled in said plate. Just below 90 the periphery of the wheel, a lug 11 is bent outwardly from the lower edge of the plate at right angles and extends just beyond the face of the disc 8.

Above the toothed disc 8 is a cutting lever 12 journaled on a pivot pin 13 anchored in the plate at a point in vertical alignment with the axis of the disc. The cutting lever has a long tapering arm extending upwardly some distance beyond the edge of the plate and 100

surmounted by a handle or knob 12a. Below the pivot pin the lever has a very short arm shaped to form first a cutting or shearing blade 14 defined by the continuation of the outer edge of the lever, an oblique shearing edge 14a and inner longitudinal edge 14b in alignment with the longitudinal center line of the lever, the blade being only one-half the width of the lever. Moreover, when the blade is in shearing or cutting position, the lever is vertical and the inner edge 14b thereof substantially coincides with a vertical line between the axes of the wheel 8 and the pivot pin 13 of the cutting lever.

This position is determined by contact between the cutting lever just below its pivot pin and a finger 15 stamped from the plate and bent to project at right angles thereto, and transversely of the path of the lever and forming an abutment which has contact with the inner edge of the lever just above and below the pivot pin, and thus limits the swinging movement of the cutting lever in both directions and to an arc of substantially 90°, that is, from the vertical cutting position to a substantially horizontal position in a counter-clockwise direction.

Another finger 16 formed integral with the cutting lever is located at the outer edge thereof that is, the edge opposite that contacting with the first mentioned finger and immediately below the pivot pin, the two fingers 15 and 16 being spaced apart about equal distances on either side of the vertical shearing edge of the blade 16, when the cutting lever is in its vertical position, and at the same distance above the lower edge of the plate.

As clearly shown in Figures 3 and 4, an ordinary can C has a bead or flange c around its rim which not only projects edgewise but also laterally in the form of a rounded head. To insert the can into the opener, the handle of the cutting lever is swung rearwardly (as shown in dotted lines in Figure 3), thus shifting the cutting blade forwardly and upwardly above the toothed wheel 8, and thus out of its cutting position overlapping the edge of the wheel. The rim of the can is then placed against the plate so that its top edge bears against the fingers 15 and 16, and the under side of the bead rests upon the periphery of the wheel. The cutting lever is now swung forwardly carrying the point of the cutting blade into contact with the top of the can just inwardly from the rim thereof, whereupon further pressure upon the lever drives the point of the shearing blade through the top wall of the can as the cutting lever is swung into its vertical position against the abutment lug 15.

Now, by turning on the crank 9, the can rotates bodily and the top thereof is sheared as it makes a complete revolution, leaving a smooth inner edge about the opening as it

is sheared. After the top has been completely sheared and removed, the can is held in one hand while the cutting lever 12 is swung backwardly, thus releasing the can from the opener.

The cutting action thus described is largely due to the presence of the finger 16 on the cutting lever, which acts to exert a downward pressure on the rim of the can and thereby force it into contact with the traction wheel with the necessary pressure to insure its rotation. In short, the finger 16 performs automatically the operation which the hand holding the can performs in the use of the so-called portable type of opener, and in the absence of other means for positively forcing the traction wheel against the rim of the can, or vice versa.

It is preferred to provide means for yieldingly holding the cutting lever in its cutting position, and for this purpose a bump 17 is stamped in the lever 12 to project from its rear face and to contact with the plate 7 as the lever is swung into its vertical position. To increase the holding capacity of the bump 17, a pair of similarly formed bumps 18, 18 are formed on the front face of the plate 7, and spaced apart to form a locking notch between. By this arrangement a slight pull or jerk upon the lever is required to bring the handle into its vertical cutting position after the blade has been forced through the top of the can and firmly holds the cutting lever in place during the cutting operation and until the opened can is released.

As a further feature of the can opener, it is contemplated that the blade may be magnetized so that any bits of metal that may be separated from the walls of the can during the opening operation, will be picked up and retained on the blade instead of contaminating the contents of the can. The possibility of such an occurrence, however, is not likely, due to the shearing action of the blade, but as a precaution the use of a magnetized blade may be provided for.

Having set forth a preferred embodiment of the invention, I claim:

1. A can opener comprising a fixed support, a traction wheel journaled in said support and having a crank for rotating the same, a lever pivotally mounted on said support and having a blade adapted to be shifted into cutting position adjacent said traction wheel by said lever, and projecting fingers located on opposite sides of said blade when in cutting position, one of said fingers being integral with said lever.

2. A can opener comprising a fixed supporting member including an upright plate, a traction wheel journaled in said plate and having a crank arm for rotating the same, a cutting lever pivotally mounted on said plate adjacent said traction wheel and having an

extended handle portion and a blade adapted to coact with said traction wheel, a finger projecting from said plate at one side of said traction wheel, and another finger projecting 5 from said cutting lever on the opposite side of said traction wheel from said first mentioned finger when said blade is in cutting position.

3. A can opener comprising a fixed supporting member including an upright plate, a traction wheel journalled on said plate to rotate against one face thereof, a crank arm connected with said traction wheel, a cutting lever pivotally mounted on said plate and 10 having a blade adapted to be swung into cutting position overlying the edge of said traction wheel, and a finger projecting outwardly therefrom on one side of said blade, and an abutment on said plate located on the opposite side of said blade from said finger when 15 said blade is in cutting position.

4. A can opener comprising a fixed supporting bracket including an upright plate, a traction wheel journalled on said plate, a 20 crank arm connected with said traction wheel, a cutting lever pivotally mounted on said plate above said traction wheel and having an extended crank arm and a blade adapted to overlie the periphery of said traction 25 wheel in cutting position, a finger bent outwardly from said plate and located at one side of said traction wheel, and a complementary finger integral with said cutting lever and located on the opposite side of said traction 30 wheel, said fingers acting as abutments for the rim of a can during the opening operation.

5. In a can opener, the combination of a fixed bracket having a horizontal arm, and 40 can-opening members mounted at the end of said arm comprising a traction wheel journalled on one side of said plate and having a crank handle, a cutting lever pivotally mounted on said plate above said traction wheel 45 and having a blade coacting therewith to penetrate the top of a can, said lever having a finger at one edge thereof projecting outwardly at one side of said cutting blade and a finger projecting from said plate on the 50 opposite side of said blade when the same is in cutting position, said fingers acting as abutments for the rim of the can during the cutting operation, and said finger on said plate also acting as an abutment for said cutting lever to hold the blade in cutting position.

6. In a can opener, the combination of a bracket adapted for mounting on a vertical or horizontal surface, an arm having angular or 60 adjustable connection with said bracket at one end and can-opening members mounted at its opposite end, the latter comprising a traction wheel having a crank handle, a lever pivotally mounted adjacent said traction wheel and having a blade coacting therewith

to penetrate the top of a can, said lever having an integral finger projecting outwardly at one side of said cutting blade and a finger projecting from said arm and located on the opposite side of said blade when the same is 70 in cutting position, said fingers acting to guide the can being opened during the cutting operation, and said last-mentioned finger acting as an abutment to limit the swinging of said cutting lever into cutting position, and means for yieldably holding said lever in cutting position.

7. A can opener comprising a fixed support, a traction wheel journalled in said support and having a crank for rotating the 80 same, and a cutting blade pivotally mounted on said support and adapted to be shifted into cutting position adjacent said traction wheel by said lever, said blade being provided with a projection extending transversely of the cutting edge thereof and offset therefrom to bear edgewise against the rim of the can during the cutting operation.

Signed at Chicago, Ill., this 18th day of February, 1931.
